UNITED STATES PATENT OFFICE

170,512

HYDRAULIC PRESS

Robert K. Sedgwick, Cincinnati, Ohio, assignor
to American Steel Foundries, Chicago, Ill., a
corporation of New Jersey

Application December 26, 1951, Serial No. 17,821

Term of patent 14 years

(Cl. D63—1)

To all whom it may concern:

Be it known that I, Robert K. Sedgwick, a citizen of the United States, residing at Cincinnati, in the State of Ohio, have invented a new, original, and ornamental Design for a Hydraulic Press, of which the following is a specification, reference being had to the accompanying drawing, forming a part thereof, wherein:

In the drawing:

Figure 1 is a front elevational view of a hydraulic press, embodying my new design;

Figure 2 is a side elevational view of the press taken from the right, as shown in Figure 1;

Figure 3 is a rear elevational view of the press; and

Figure 4 is a top plan view of the press.

The essential features of my design reside in the portions shown in full lines.

I claim:

The ornamental design for a hydraulic press, substantially as shown and described.

ROBERT K. SEDGWICK.
